Samuel P. Glunt.

UNITED STATES PATENT OFFICE.

SAMUEL P. GLUNT, OF UNION CITY, INDIANA.

SLIDING-DOOR FASTENER.

1,162,232.

Specification of Letters Patent. Patented Nov. 30, 1915.

Application filed September 24, 1914. Serial No. 863,488.

To all whom it may concern:

Be it known that I, SAMUEL P. GLUNT, a citizen of the United States, residing at Union City, in the county of Randolph and 5 State of Indiana, have invented a new and useful Improvement in Sliding-Door Fasteners, of which the following is a specification.

My invention relates to improvements in 10 sliding doors used on closed top vehicles, commonly called storm buggies; and the object of my invention is to provide a locking device for sliding doors which shall securely lock the door when closed, or partly closed, 15 or when opened to its farthest extent; also a device which, when applied, prevents the door from rattling.

The nature of my invention will be readily comprehended, reference being had to the 20 following detailed description and to the accompanying drawings.

In the drawings, Figure 1 is a perspective of a part of the inside of the buggy body, showing my locking device applied to the 25 door. Fig. 2 is a sectional view taken at the front edge of the seat, showing in detail a part of my device applied to the door, the door being open to its fullest extent. Fig. 3 is a detail of a curved piece of iron over 30 which a foot pedal slides, the foot pedal being attached to a carrying track. Fig. 4 is a detail of a pocketed casting which secures the ends of the carrying track to the buggy body.

35 Referring to the drawing by numerals 1 is the sliding door which opens and closes the entrance to the buggy.

2 is the side quarter of the closed top.

3 is the end panel of the buggy seat.

40 4 is the fall board which forms a part of the frame work of the buggy body.

5 is the bottom of the seat.

6 is a part of the frame work of the buggy body.

45 7 is the sill of the buggy body.

8 is a corner post which forms a part of the frame work of the buggy body.

9 is the side panel of the buggy body.

10 is a carrying track which is made to 50 rock by a foot lever, 12, when it is pressed forward on curved iron, 11, and by its con-

nexion with 15 through 14, presses upward against 16 which through 17 presses outward against the door and the friction thus created holds the door in any desired position 55 and prevents its rattling. The rocking motion of 10 is reversed by placing 11 above 10, which is the preferable position for 11, and through 12, 10, 14, 15, 16 and 17 the door is drawn inward when 12 is pushed forward on 60 11 and is securely held against the side quarter of the buggy top, thereby preventing all rattling of the rear side of the door.

11 is a curved plate of iron, attached to the side panel at one of its ends and to the 65 corner post of the body at the other end, and by its curved shape deflects the end of 12 as it moves forward on 11, thereby rocking 10 to the right or left according as 11 is placed above or below 10.

70 12 is a foot pedal, which, when pressed forward on 11, rocks 10, and through 10, 14, 15, 16 and 17, draws 1 inward. 12, by the rocking motion which it gives to 10, creates friction in the loop 13, thereby holding the 75 door in whatever position placed, and at the same time prevents rattling.

13 is a yoke by means of which 1 is attached to 10.

14 is an arm set at right angles to 10, connects 10 and 15 and gives 15 an upward or downward movement when 10 is rocked by the forward movement of 12 on 11.

80 15 is a bar connecting 14 and 16 and when operated through 10 and 14 by the forward 85 movement of 12 on 11, operates 16 and 17, which draws the door inward or presses it outward.

16 is a bell crank, or angular lever, which is attached to 2 by means of a screw. It is 90 connected with 15 and 17 by rivets, and when operated through 15, 14, and 10 by the forward movement of 12 on 11, draws the door inward or pushes it outward.

95 17 is a short bar with a button 22 at one end, is attached to 16, and engages 18 and 18 and is drawn inward or pressed outward through 16, 15, 14 and 10 when 12 is pressed forward on 11, thereby drawing the door inward or pushing it outward.

100 18 and 18 are bars attached to the door at right angles to its edges and spaced apart to

form a slot, into which, 17 is buttoned. When the pressure of the button on 17 against 18 and 18, caused by the forward movement of 12 on 11, is removed by the backward movement of 12 on 11, the door then can be moved freely backward and forward.

19 is a pocketed casting which attaches each end of 10 to 9.

10 20 is open space under the buggy seat.

21 is the bottom of the buggy body.

The yoke, parallel bars, bar with button and the bar to which the door is yoked described in the foregoing specification and 15 for which Patent No. 990252, was granted to me April 25th, 1911, and Patent No. 1,067, 871, was granted to me July 22nd, 1913, are not claimed as being new. The rocking feature of the bar, the foot pedal and the side 20 arm being new.

Having thus described my invention, what I claim is—

A sliding vehicle door combined with a rocking bar having a foot pedal attached and a lateral arm attached, a deflecting iron 25 on which one end of the foot pedal slides, a bell crank or angular lever, and a connecting bar joining the rocking bar and the bell crank or angular lever, a yoke connecting the door with the rocking bar, two bars extending crosswise the door, parallel to each other, thus forming a slot between them, and a short bar having a button at one end, this bar connecting the bell crank or angular lever with the two parallel bars, substantially as described.

SAMUEL P. GLUNT.
